United States Patent Office

Des. 198,160
Patented May 12, 1964

198,160

CHEMICAL EXTRACTOR

John E. Thompson, P.O. Box 2023, Chicago 9, Ill.

Filed May 21, 1963, Ser. No. 74,983

Term of patent 7 years

(Cl. D16—1)

FIGURE 1 is a side elevational view of a chemical extractor, showing my new design.

FIGURE 2 is an elevational view taken from the right of FIGURE 1; and

FIGURE 3 is a top plan view thereof.

I claim:

The ornamental design for a chemical extractor, substantially as shown.
